UNITED STATES PATENT OFFICE.

JOHN WINKLER, OF PHILADELPHIA, PENNSYLVANIA.

WATER-COOLING ATTACHMENT FOR AUTOMOBILE RADIATORS AND THE LIKE.

Application filed January 3, 1922. Serial No. 526,571.

To all whom it may concern:

Be it known that I, JOHN WINKLER, a citizen of the United States, residing in the city and county of Philadelphia, State of Pennsylvania, have invented a new and useful Water-Cooling Attachment for Automobile Radiators and the like, of which the following is a specification.

My invention consists of a novel construction of an appliance adapted to be readily attached to any conventional type of automobile radiator or radiator cap for the purpose of increasing the efficiency or cooling capacity of the system, means being provided for introducing the atmospheric air into suitable channels or conduits, open at their front and closed at their rear and front bottom portions, and contained in a frame or body constituting the air collecting device, which is carried by or secured upon a radiator cap of any conventional type, whereby a plurality of the air currents are collected and concentrated or discharged into one common discharge outlet and caused to travel downwardly through a pendant air tube into the water chamber of the radiator through ports in said pendant air tube or pipe, provision being further made for enabling the height of the water in the radiator at all times to be readily ascertained.

It further consists of a novel manner of securing and locking the pendant air tube in the radiator cap, the upper portion of said tube being threaded so as to provide a ready means for connecting the air collecting device thereto.

It further consists of other novel features of construction, all as will be hereinafter fully set forth.

For the purpose of illustrating my invention, I have shown in the accompanying drawings a form thereof which is at present preferred by me, since it will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a water cooling apparatus for an automobile radiator and a portion of the radiator to which the same is applicable.

Figure 2 represents on an enlarged scale a front view of the attachment seen in Figure 1 in detached position.

Figure 3 represents a side elevation of 60 Figure 2, the upper portion thereof being in section.

Figure 4 represents a section on line 4—4 of Figure 3.

Similar numerals of reference indicate 65 corresponding parts.

Referring to the drawings,

1 designates the radiator of an automobile or other engine and 2 the cap or closure therefor, to which my novel cooling device 70 is applied.

In carrying out my invention, I employ a radiator cap cut with a hole in it and insert therethrough the pendant air pipe or tube 3 having its upper end 4 threaded and its 75 lower end provided with the air exit ports 5, which communicate with the upper portion of the radiator chamber, said tube being secured in position in the radiator cap by the upper and lower lock nuts 6 and 7. 80

8 designates the air receiving and collecting device which comprises a frame which is open in its centre forming a chamber which is annular, horseshoe or other shape and is provided with the open air receiving channels or conduits 9 preferably composed of two conduits which are open at their front and closed at their rear and bottom front portions and discharge downwardly into the central common conduit or passage 10 and 90 thence into the pendant air receiving tube 3, said passage 10 being interiorly threaded and screwed upon the threaded upper portion 4 of the tube 3.

11 designates a float positioned in the tube 95 3 to rest on the water in the radiator, it having connected with it the rod or stem 12 which projects upwardly therefrom through the hole 13 of the wall 14, said rod terminating in the head 15 which acts as a stop when 100 it reaches the wall 14 to limit the descent of the rod 12 and the float 11. The upper end of the rod or stem 12 is visible in the central space of the air collecting frame 8 where it serves as a tell-tale of the condition of the 105 water in the radiator due to the action of the float 11.

It will be apparent that in carrying out my invention, it is only necessary to employ a cap for the radiator having therein an 110 opening and inserted therethrough the air conveying tube 3, it being securely held in

position with respect thereto by the lock nuts 6 and 7. The frame 8 which contains the air collecting channels, passages or conduits is then screwed upon the upper threaded 5 end of the air pipe or tube 3, so that the parts when in assembled position appear as seen in Figures 1 and 4, and by making the air collecting device in the shape of a horse-shoe or the like, a pleasing and ornamental 10 effect is obtained at the top of the radiator.

It will be apparent that as the automobile progresses, the air currents which are caught in the annular channel 9 will flow downwardly through the exit passage 10 into the 15 pendant air tube 3 and out through the ports 5 into the upper portion of the radiator chamber, thereby cooling the water therein.

By my manner of assembling the elements 20 with respect to the radiator cap 3, it will be apparent that all the parts are securely locked in assembled position, and can be removed or replaced as a unit when it is desired to replenish the water in the radiator.

16 represents screens which are placed in 25 the channels 9 near the bases thereof to prevent the entrance of dust and foreign substances into the body of the radiator. The conduit 10 is extended upwardly by the wall 30 17 so as to close the lower portions of the

channels, and said screens 16 are in the channels adjacent to the top of said wall so as to trap said substances and prevent them from entering the conduit and consequently said body.

My device can be readily assembled without necessitating the employment of skilled labor and is readily applicable to any standard radiator cap or radiator and will be efficient, durable and reliable in its action, as 35 40 is evident.

Having thus described my invention, what I claim as new and desire to secure by Letters Patent, is:—

In a device of the character stated, the 45 combination of a substantially horse-shoe shaped casing having a contracted neck which has an internally screw-threaded opening, said casing having a continuous channel therein in communication with said opening, a radiator cap having a screw-threaded opening therethrough, a tube the lower wall of which is perforated and which tube is screw-threaded at its opposite end to engage 50 55 said cap and neck and means for clamping said tube with respect to said cap.

JOHN WINKLER.
